METHOD OF CORE DRILLING

John Branner Newsom, Nevada City, Calif., assignor to Idaho Maryland Mines Co., San Francisco, Calif., a corporation of Nevada

Application April 8, 1935, Serial No. 15,226

2 Claims. (Cl. 255—72)

This invention relates to drills for sinking shafts such as mine shafts, and in particular to a core drill. It has been the practice for many years to sink large size shafts such as mining shafts by means of explosives, and it is well known that the walls of a shaft sunk in this manner are rough and irregular and consequently have to be timbered. In a mine of any size a crew has to be maintained for the sole purpose of replacing the shaft and tunnel timbers. Small diameter core drills have been used for many years, and are familiar to most mining engineers. However, these drills have been used mainly for sampling and for providing passages for liquid. As far as I am aware, a core drill has never been designed and successfully employed prior to the development work on which this application is based, for drilling large diameter shafts in the order of five foot or larger, and to the depth required for mining operations.

One of the objects of this invention is the provision of a method of sinking a large diameter shaft in which a core drill is employed.

Another object of the invention is the provision of a mechanism for sinking a large diameter shaft comprising a cylindrical pilot house; a drive shaft depending from the pilot house and secured at its lower end to a core drill; and means within the pilot house for rotating said shaft and controlling its vertical movement.

Another object of the invention is the provision of a core drill provided with a relatively movable pilot house which may be occupied by an operator during the actual drilling operations.

Still another object of the invention is the provision of means for collecting the drilling cuttings during the drilling operation.

The invention possesses other advantageous features, some of which with the foregoing, will be set forth at length in the following description where that form of the invention which has been selected for illustration in the drawings accompanying and forming a part of the present specification is outlined in full. In said drawings, one form of the invention is shown, but it is to be understood that it is not limited to such form, since the invention as set forth in the claims may be embodied in a plurality of forms.

Referring to the drawings:

Figure 1 is a longitudinal cross section of a shaft drill embodying the objects of my invention.

Figure 2 is a longitudinal cross section of a shaft drill taken at right angles to the drill shown in Figure 1.

Figure 3 is a plan view of the drill shown in Figure 1.

Figure 4 is a section taken on the line 4—4 of Figure 2.

Figure 5 is a plan view of the spider shown intermediate the pilot house and core drill in Figure 1.

Figure 6 is a cross section taken on the line 6—6 of Figure 1.

Figure 7 is a fragmentary view of the cutting member of the core drill.

Figure 8 is a diagrammatic view of my shaft drill in position for drilling at the beginning of a new cycle.

Figure 9 is a diagrammatic view of my shaft drill at the end of a drilling operation.

Figure 10 is a diagrammatic view of a shaft with the shaft drill removed and the core in position to be broken away from its base.

My invention contemplates the use of a cylindrical pilot house 1 within which is suspended a drive shaft 2, to which is secured at its lower end a core drill 3. The pilot house and the core drill are preferably made from $\frac{1}{2}$ " plate, and the pilot house is reinforced by means of channel bars 4, 5, 6, and 7, welded or otherwise secured thereto. Supported by the channel bar 7 are a pair of spaced I-beams 8 and 9 which in turn support the bearing members 11 and 12. The channel bar 6 supports a wood flooring 13 and also a pair of spaced channels 14 and 15, which in turn support a plate 16. Depending from and secured to the plate 16 is a bearing 17 in alignment with the bearing 11 and within which the shaft 2 is adapted to rotate. Keyed to the shaft 2 between the bearings 11 and 17 is a bull wheel or gear wheel 18 adapted to be driven by a pinion 19 carried by the shaft 21, which in turn is supported by bearings 22 and 23. Secured to the intermediate portion of the shaft 21 is a gear 23 adapted to be driven by the belt 24 which passes over the pulley 25 of the motor 26. As shown in Figures 1 and 2, the motor 26 is supported by the channel bars 14 and 15. Extending upwardly from the plate 16 is a rectangular frame made up of channel bars 26' which may be secured to the plate 16 and to the roof or ceiling 27 of the pilot house in any suitable manner, such as for example by angle bars 28 and plates 29. Secured to the lower side of the roof 27 are a pair of spaced brackets 31 which serve as bearings for the shaft 32 to the outer ends of which are secured pulleys 33. Slidably disposed within the rectangular frame formed by the channel bars

35

40

45

50

55

26' is a block 34 which is adapted to engage the collar 35 bolted or otherwise secured to the shaft 2. The block 34 and in turn the shaft 2 is adapted to be lowered and raised by a winch 36 operatively connected to the block 34 by ropes or cables 37.

Disposed at spaced points within the channel bars 4 and 5 are a plurality of wall jacks consisting of nuts 38 held in position by clips 39 and 10 screws 41 passing through the nuts and adapted to be driven into the walls of the shaft 42.

The function of the screws 41 is to center and level the cylindrical pilot house 1 within the shaft and to simultaneously anchor it within 15 the shaft in its centered position. As an aid in leveling the pilot house, spirit levels may be conveniently located on its framework.

The core drill 3 is closed at its upper end by a plate 44 to which is secured a collar 45 which 20 in turn is bolted to the lower end of the shaft 2 as clearly shown in Figure 1. A manhole 46 is provided in the plate 44 adapted to be closed by a cover 47. The lower end of the core drill 3 is formed with a suitable cutting edge 48 25 adapted to cooperate with the customary steel balls.

Intermediate the pilot house 1 and the core drill 3 is a spider generally designated as 49, comprising a frame 51 adapted to carry a plurality of spaced screws 52. The center of the frame 51 serves as a bearing for the shaft 2, and therefore it will be seen that the spider 49 may be used to prevent the shaft 2 from whipping when the core drill is in its extended 35 position. Although not shown the spider 49 is provided with means for suspending it from the pilot house and holding it in any predetermined position while the screws 52 are being adjusted. When the core drill 3 is raised the frame 51 of 40 the spider is supported on the angle iron 53 secured to the plate 44 while the pilot house 1 rests against blocks 54, carried by the frame 51.

As best shown in Figure 3 the plate 27 which forms the ceiling of the pilot house 1 is provided with trap doors 55 and 56 through which 45 an operator may pass in order to gain entrance to the pilot house. The upper periphery of the shell of the pilot house 1 extends above the ceiling 27 and is bent inwardly as at 57 (Figures 50 1 and 2) so that the pilot house may be pulled upwardly within the shaft. In effect this upper periphery of the pilot house shell forms a guide member for the pilot house during its upward movement through the shaft. To the upper end 55 of the shaft 2 is bolted a ring 58 to which a cable may be secured for the purpose of raising and lowering the entire mechanism, and also for the purpose of suspending the shaft drill in any predetermined position. Ordinarily the 60 screws 41 serve to anchor the pilot house in position, but as a safeguard it is advisable to keep the cable secured to the ring 58 taut so that if by any chance the screws 41 give way there will be no danger of dropping the entire 65 mechanism.

The operation of the mechanism is as follows: The bottom of the shaft or drill hole 42 is cleaned out and then a bucket 63 having a bail 64 is lowered to and seated on the bottom 70 of the shaft. The shaft drill is lowered to the bottom of the shaft 42 by means of the cable secured to the ring 58, so that the core drill 3 rests on the floor of the shaft and over the bucket 63. The pilot house is then centered within the shaft and anchored therein by means

of the screws 41. The operator who is standing on the floor 13 of the pilot house starts the electric motor 26 which is supplied with electric current by means of suitable cables, passing upwardly through the ceiling of the pilot house, to 5 the top of the shaft. Preferably the motor 26 should be of the variable speed type. Obviously the rotation of the motor operates to rotate the shaft 2 and consequently the core drill 3. As 10 is the usual practice, steel shots are periodically introduced to the cutting edge 48 of the core drill and this is preferably accomplished by introducing the shot between the walls of the shaft 42 and the outer base of the core drill 3. It is for this reason primarily that the upper 15 end of the core drill has been entirely closed by means of the plate 44 and the trap door 47. At this time the spider 49 may be allowed to 20 rest on top of the core drill 3. The core drill is then gradually lowered as the drilling progresses, by means of the winch 36. In this connection it should be particularly noted that since the core drill is about ten feet long the operator is always within 20 or 25 feet of the cutting edge of the core drill. This is of considerable 25 importance for the rate of lowering the core drill depends entirely upon the nature of the rock through which the shaft is being sunk, and this in turn can only be determined by 30 sound, by the heat generated in drilling, and by the manner in which the drill appears to be operating. The rate at which drilling is allowed to progress is largely a matter of experience, but the judgment of the operator is materially increased by being close to the point 35 of operation rather than at a remote distance as is the case in most drilling operations. After the core drill 3 has progressed several feet it may then be advantageous to adjust the spider 49 intermediate the core drill and the pilot 40 house for the purpose of preventing any whipping or lashing of the shaft 2. This may be done by the operator by lowering himself through a trap door in the floor 13, and lowering the spider 49 to the desired point by means 45 of suitable cables as above described and then adjusting the screws 52. The drilling operation produces cuttings in the form of heavy sand which are collected as the drilling progresses in the bucket 63 resting on top of the core. The 50 rotation of the core drill causes the water in the shaft to swirl and to thereby deposit the sand in the bucket. The capacity of the bucket should be sufficient to hold all of the cuttings formed during one complete cycle of operation. When 55 the core drill 3 has completed its full strike of 10 feet or so as shown in Figure 9, the entire mechanism is hoisted from the shaft, leaving the core 59 extending upwardly from the bottom of the shaft as shown in Figure 10 with the 60 bucket 63 resting on top of the core. The water is pumped from the shaft, the bucket 63 raised to the surface by means of the bail 64, and then the operator is lowered to the upper face of the core and by means of a wedge 61 breaks the core 65 away from the lower end of the shaft, as shown at 62. The core 59 may then be removed either in a single piece or in several pieces as the case may be. When this has been done the operation is again repeated to thereby sink the shaft 70 another 10 feet, the second core is removed and the operation repeated until the shaft is sunk to any desired depth.

If the motor should burn out, noxious gases would be produced which might suffocate the

operator. Furthermore, considerable heat is developed during the drilling operation. For these reasons it has been found desirable to provide the pilot house with a valved air line 5 extending from the top of the shaft so that a controlled supply of air may always be available.

"Cylindrical" as herein used in reference to the pilot house is not to be construed as limited to a circular cylinder but rather in its broad 10 geometric sense. As a matter of fact the pilot house may consist of merely a suitable frame work covered at the top to protect the operator and containing the working mechanism above described.

15 I claim:

1. The method of collecting cuttings from a

shaft during the operation of a core drill under water comprising placing a bucket on top of the core and rotating the drill to cause the water to swirl and thereby lift the cuttings into the bucket.

2. The method of collecting the cuttings resulting from the operation of a rotary core drill in drilling a shaft comprising: rotating the core drill in the shaft; maintaining a bucket on top of the core; and maintaining the water level 10 in the shaft above the core so that the swirling motion imparted to the water by the rotation of the core will deposit the cuttings within the bucket.

JOHN BRANNER NEWSOM. 15
